(57) **CLAIM**

The ornamental design for a sling mount, as shown and described.

DESCRIPTION

FIG. 1 is a perspective view of a sling mount embodying my new design;

FIG. 2 is a frontal view thereof;

FIG. 3 is a rear view thereof;

FIG. 4 is a side view thereof;

FIG. 5 is a side view thereof;

FIG. 6 is a top view thereof;

FIG. 7 is a bottom view thereof;

FIG. 8 is a perspective view of a sling mount attached to a Picatinny rail; and,

FIG. 9 is a close up view of a sling mount attached to a Picatinny rail.

The riflescope mount is shown in context with broken lines for illustrative purposes only and forms no part of the claimed design.
